GRINDING MACHINE

Walde J. Guild, Worcester, Mass., assignor to
 The Heald Machine Company, Worcester,
 Mass., a corporation of Massachusetts

Application July 20, 1931. Serial No. 551,922

33 Claims. (Cl. 51—215)

The present invention relates to grinding machines and particularly to internal grinding machines arranged for the automatic finishing of the internal bore of successive workpieces to a predetermined diameter and for mechanically inserting successive unground workpieces into and removing finished workpieces from the workholder.

In the copending application of Highborg, Serial No. 99,287, filed April 2, 1926, now Patent No. 1,840,841 the grinding wheel is withdrawn from the workpiece and run out a substantial distance from the workholder upon the completion of the grinding operation. At the end of the runout, the movement of the carriage carrying the grinding wheel is automatically reversed in response to the carriage movement, whereby the wheel is returned into operative relation to the workpiece. During the runout and return of the wheel, a workloading device is operated in response to the carriage movements in order to effect the removal of the completed workpiece from the workholder and the insertion of an unground workpiece therein. In a machine of this type, if any of the parts fail to function properly, the unloading and loading of the workholder is not completed before the wheel returns to operative position and the mechanism jams or the subsequent entire grinding operation is carried through without a workpiece having been inserted in the holder. One of the objects of the present invention is to provide an automatic grinding machine which incorporates the advantages of a machine of the type disclosed in the above cited application with none of its disadvantages.

According to the present invention, the carriage carrying the grinding wheel is run out to rest position and initiates during the runout, the operation of the workloading instrumentalities; the latter proceed to remove the completed workpiece from the workholder and insert an unground workpiece therein, the carriage being returned toward the workholder to bring the grinding wheel into operative position only when the loading mechanism has completed its operation. The workloading mechanism is arranged to go through the entire operation of removing the completed workpiece from the workholder and inserting an unground workpiece therein entirely independently of the operation of the grinding instrumentalities, that is, after the workloading instrumentalities are put in operation, the operation is continued and carried to completion by instrumentalities forming an integral part of the workloading mechanism, the grinding instrumentalities

being set in operation automatically at the completion of the loading operation.

The invention incorporates automatic grinding machine instrumentalities which are arranged to procure the grinding of successive workpieces each to a predetermined finished size as shown by way of example in the patent to Taylor 1,682,673 issued August 28, 1928, the patent to Kempton and Gallimore No. 1,731,719 issued October 15, 1929, or the copending application of Guild and Burns Serial No. 367,401 filed May 31, 1929, now Patent No. 1,830,358, issued November 3, 1931, each of which is arranged to grind successive workpieces to a predetermined size when said workpieces are inserted in the workholder, the machine being brought to rest at the completion of each grinding operation. The present invention involves automatic mechanism by which to return the grinding wheel carriage to the work when an unground workpiece has been loaded into a workholder by the workloading mechanism. Another object is to provide a grinding machine in which the various instrumentalities are actuated by fluid pressure mechanism. Other objects and advantages of the invention will appear as from the following description taken in connection with the accompanying drawings.

Like reference characters refer to like parts 10 throughout the drawings.

Referring to the drawings, particularly to Fig. 1, the machine provides the usual reciprocatory table or carriage 1, ordinarily provided in internal grinding machines. In such a machine 15 either the grinding wheel or the work to be ground may be carried on the table 1, the reciprocation of the latter being utilized in either case to produce a relative traversing movement between the grinding wheel and the work. As here shown, the 20 table 1 supports and carries a wheelhead 2 of the usual construction while the work which is to be operated upon is held in a chuck or other suitable work-supporting and rotating mechanism in a workhead 3, the latter being carried by a bridge 25 4 which spans slideways, not shown, provided by the machine frame for the back and forth movement of the table 1.

The machine of the present invention utilizes certain mechanisms from prior patents which are 30 briefly referred to in order more completely to understand the invention. A rotating gauge of the type disclosed in Reissue Patent No. 16,141 granted to McDonough August 11, 1925, is used to bring the grinding operation on each successive 35 workpiece to a close when the workpiece reaches a predetermined finished size. The automatic dressing and truing of the grinding wheel by which a true grinding surface is maintained, is procured by mechanism of the type disclosed in Patent No. 1,731,719, granted to Kempton and 40 Gallimore October 15, 1929, the automatic dressing operation being inaugurated by instrumentalities similar to the type disclosed in Patent No. 1,682,672 granted to Guild, the present applicant, 45 August 28, 1928. The arrangement of the mechanism which controls the grinding operation on each workpiece is disclosed in the above identified copending application of Guild, the present applicant, and Burns, Serial No. 367,401, filed May 31, 50 1929, and the application of Guild, the present applicant, Serial No. 445,989, filed April 21, 1930, now Patent No. 1,914,995, dated June 20, 1933. A brief description of the general operation of the machine in accordance with these prior patents 55 and applications will be given in order to disclose a completely automatic grinding machine.

The grinding wheel carriage is arranged for reciprocatory movement longitudinally of the table 1 in order to procure a traversing movement 60 of the grinding wheel carried by the wheelhead across the surface of the workpiece being ground, and to this end the machine provides a cylinder 5, Fig. 15, which is preferably attached to the base of the machine, the cylinder containing a piston, 65 not shown, whose piston rod 6 is connected to the carriage 1. Fluid under pressure is directed alternately to opposite ends of the cylinder 5 by mechanism hereinafter disclosed to procure the reciprocatory traverse of the carriage.

70 The normal reciprocatory traverse to procure the working reciprocation of the grinding wheel in operative relation to the workpiece is procured in the manner disclosed in the above cited Guild Patent No. 1,914,995, by dogs or stops 7 and 8, 75 Fig. 2, carried on the front of the carriage 1,

said dogs being arranged alternately to engage with the upwardly extending arms 10 and 11 of a reversing member 12, Fig. 15, thereby actuating said member to direct fluid under pressure alternately to opposite ends of the cylinder 5 in order to actuate the carriage alternately in opposite directions. The reversing member 12 is arranged to operate a pilot valve 13, the latter in turn controlling a main valve 14 which provides fluid connection from a pump 15 to alternate ends of the cylinder in the following manner:—

80 Referring to Fig. 15, the pilot valve 13 comprises a valve casing 16 having a cylindrical bore therein which receives the valve 13. Pressure fluid is admitted to the casing 16 by means of a pair of conduits 17 and 18 which are connected to the source of fluid pressure, or pump 15 by the fluid supply line 20. The valve casing 16 is provided with outlet ports 21 and 22 which are connected to opposite ends of the main valve 14 by pipes 23 and 24, and an exhaust port 25. The reversing member 12 engages the projecting end of valve 13 whereby, in response to movement of said member 12, fluid connection is alternately provided from the pump to opposite ends of the main valve, at the same 100 time connecting the opposite end of the main valve to the exhaust port 25.

90 Referring to Fig. 15, the main valve 14 which is attached to the front of the machine slidably receives the main valve 14, the latter comprising a hollow 105 cylindrical member, the ends of which are closed by plugs, a divisional wall 27 being provided between these plugs to divide the interior of the valve into two chambers. The valve 14, being slidable within the valve casing, is urged alternately to its end positions in response to movement of the pilot valve 13 by which movement, fluid under pressure is admitted to opposite ends of said main valve casing. The fluid under pressure, for actuating the carriage 1, is introduced 110 to the main valve from the supply line 20 through a pipe connection 28 to a valve mechanism 30 which is arranged to control the speed of the reciprocatory movement as fully disclosed in Patent No. 1,914,995 above cited. Said valve, however, forms no part of this invention, and may be considered as remaining in the full open position shown during the machine operation. From this valve 30, the fluid flows through a channel 31 in casing 26 past a manually controlled throttle valve 115 32 to an inlet port 33 adjacent the left hand end of the casing 26 for the valve 14 and a second inlet port 34 adjacent the right hand end of said casing. Said casing also provides outlet ports 33' and 34' connected by pipes 35 and 36 to opposite ends of the cylinder 5. With the valve 14 in the position shown in Fig. 15, it will be apparent that fluid may flow directly from the pump 15 through valve 14 to the left hand end of the cylinder 5, the fluid from the right hand end of said cylinder exhausting through the valve 14 into the exhaust pipe 35' so that the table is moved toward the right, during which movement the dog 7 engages and actuates the reversing member 12, thereby moving the pilot valve to the left 120 and providing a connection for fluid from the pump to the left hand end of the valve 14. This movement of the pilot valve admits fluid to the left hand end of the casing 26 and thereby actuates the valve 14 to the right to establish a fluid 125 connection from the pump 15 to the right hand end of the cylinder 5, thereby actuating the table to the left, the alternate movements of the carriage to right and left moving the grinding wheel 130 over the work surface.

During the preliminary grinding operation, the grinding wheel and the workpiece are moved transversely relative to one another, thereby to urge the grinding wheel deeper and deeper into cutting relation to the surface being ground, this movement being effected by mechanism similar to that disclosed in the above cited Patent No. 1,830,353. For the purposes of the present invention, it is sufficient to note that the workhead 3 is mounted 10 in transverse guideways, not shown, provided by the bridge 4 so that it may be moved transversely to the direction of travel of the table or carriage 1. The feeding movement is procured by ratchet and pawl means which are provided and 15 which are actuated by a piston and cylinder arrangement actuated by movement of the main valve 14 in order to procure intermittent angular movement of a screw shaft 37 which cooperates with a nut element associated with the workhead 20 3 to produce the transverse movement of the workhead. Desirably, a hand wheel 38 is fastened to the forward end of the shaft 37 for manual adjustment of the position of the workhead 3.

25 The transverse feeding movements of the workhead 3 to procure successively deeper and deeper cuts on the workpiece and the reciprocating movement of the grinding wheel over the workpiece are wholly automatic and continue until the workpiece is ground to a predetermined preliminary size, at which time the wheel is withdrawn 30 from the work to procure a dressing or truing operation thereon, prior to the final cuts which bring the workpiece to finished size. The extended movement of the wheel in order to perform the truing operation is obtained in response to mechanism of the type disclosed in the above cited patent to Guild No. 1,682,672. It is sufficient to note, for purposes of the present invention, that a cam 40, Fig. 14, is mounted for rotation with the above mentioned ratchet wheel, the latter being indicated diagrammatically at 41 in Fig. 14, and as the ratchet wheel is rotated clockwise, thereby procuring intermittent cross-feed 40 movement of the work relative to the grinding wheel, said cam is carried therewith and is ultimately brought into engagement with an adjusting screw 42 supported by a pivotally mounted arm 43. Actuation of the screw 42 and accordingly rotation of the arm 43 makes an electrical contact which procures separation of the grinding wheel from the workpiece and brings the dressing tool, not shown, into operative position for the dressing operation on the grinding wheel.

55 As shown in Fig. 14, the arm 43 is grounded at 44 and has an electrical contact 45 thereon which, in response to movement of the arm, is brought into engagement with a stationary contact 46, the latter being connected by a lead 47 to one plate 48 of a switch member 50. Said switch is pivotally supported on the front of the frame and is normally in the position shown in Fig. 14 in which position the plate 48 is in engagement with a stationary plate 51 connected by a lead 52 to a terminal of an electromagnet 53, the other terminal of the electromagnet being connected by a lead 54 to one terminal of a generator 55, the other terminal of which is grounded at 56. Actuation of the arm 43 energizes the electromagnet 53, thereby causing attraction of an armature member 57 pivotally mounted at 58 on the front of the frame. Attraction of the armature member rotates a depending arm 60 counterclockwise, thereby moving a valve 61, Fig. 15, connected thereto to the right.

The valve 61 is arranged to procure an extended movement of the grinding wheel carriage to carry the grinding wheel past a dressing tool and simultaneously to move the dressing tool into operative position where it may engage the grinding wheel during its extended movement. The valve 61 operates in the manner set out in the above cited Patent No. 1,914,995. For the purposes of the present invention, it is sufficient to note that the valve 61 is mounted in the pipe line 23 which connects the pilot valve 13 to the left hand end of the main valve 14. The valve 61 is normally in the position shown in Fig. 15 in which position fluid in the pipe 23 is allowed to flow directly through said valve 61 to the main valve 14. When the valve is actuated to the right, however, in response to swinging movement of the depending arm 60, the pipe 23 from the main valve 14 to the valve 61 is put in communication with an exhaust port 62 in the valve casing 63, whereby movement of the main valve to the left may occur at any time, the fluid in the left end of said valve exhausting through port 62, but the main valve will not again be actuated to the right in response to movement of the pilot valve since the connection between said pilot valve 13 and the valve 61 is out of communication with the pipe 23 from the valve 61 to the main valve, the valve 61 having closed the port where the connection from the pilot valve enters said valve 61. It therefore follows that at the end of the leftward movement of the carriage, following movement of valve 61 to the right, the reversing lever 12 will be shifted as usual and the pilot valve 13 will be moved to the right into the position of Fig. 15 which will cause fluid to be admitted to the right hand end of the main valve 14, thereby to shift said valve to the left to actuate the carriage toward the right. The subsequent reshifting of the reversing member 12, however, as the carriage travels to the right, which results in the movement of the pilot valve 13 will not be effective to move the main valve 14, the connection 23 between the pilot valve and the main valve being cut off by movement of the valve 61 as above pointed out. The carriage, therefore, continues its movement to the right carrying the grinding wheel out of the workpiece, said carriage being ultimately reversed as will be hereinafter described.

125 The other function of the valve 61 is to cause the diamond or dressing tool, not shown, to be lowered into the path of the grinding wheel. When the valve 61 is moved to the right, as above pointed out, fluid connection is provided from the pump to a cylinder 64 through the casing 63, the fluid being supplied to said casing from the pump by a pipe 65 and from the casing to the cylinder 64, by a pipe 66, said cylinder having a piston 67 mounted therein which is actuated in response to movement of the valve 61, the fluid connection to cylinder 64 being closed in the normal position of the valve 61 as shown in Fig. 15. Movement of the piston 67 procures swinging movement of a diamond or dressing tool into operative relation to the grinding wheel in the manner described in the Heald and Guild Patent No. 1,779,094, issued October 21, 1930. As the carriage is moved to the right, the grinding wheel is carried into engagement with and beyond the dressing tool, at which time the direction of movement is reversed and the carriage is returned toward the work to bring the grinding wheel again into operative relation thereto. This reversal of the carriage is effected by move-

ment of the valve 61 in the following manner:—

- The pilot valve having been shifted by the reversing lever 12 during the outward or right hand movement of the carriage is in a position to cause the carriage to return the grinding wheel to the left into the workpiece upon return of the valve 61 to its original position. It will be remembered that the valve 61 is held in its right hand position by the magnet 53, and in order to release the valve, the magnet is deenergized during the outward movement of the carriage away from the workpiece. An arm 68, Fig. 14, pivotally mounted on a carrying block 70 on the carriage, and hanging by gravity in the position shown, engages a lug 71 on the pivotally mounted switch 50 during the right hand extended movement of the carriage, thereby disengaging the plates 48 and 51 and breaking the circuit through the electromagnet 53. This movement of the switch 50 releases the armature 57, thereby to permit return of the valve 61 to its original position, the return of the valve being effected just after the grinding wheel has passed the dressing tool during the right hand movement of the carriage. A block 72, Fig. 2, which, the same as the carrying blocks 73 and 74 for the dogs 7 and 8, is adjustably mounted on the front of said carriage, supports a striking dog 75 which is attached to said carrying block, and a projecting arm 76 of the armature 57 is in the path of travel of the dog 75. It will be seen that movement to the right of the carriage will cause engagement of the dog 75 with the arm 76, said engagement occurring directly after the grinding wheel has passed the dressing tool on the right hand stroke, and will accordingly forcibly reposition the armature and accordingly the depending arm 60, thereby moving the valve member 61 into the original position to establish fluid connection from the pilot valve 13 to the left hand end of the main valve 14. As soon as the valve member 61 is repositioned, the main valve is shifted by the fluid passing through the pipe line 21 to the left hand end of said valve and the movement of the carriage is reversed, whereby the grinding wheel is returned to the workpiece for the completion of the grinding operation.

During the continued grinding on the workpiece, after the dressing operation to bring said workpiece to finished size, the traversing movement continues and the workhead is again intermittently moved transversely of the machine to provide a cross-feed movement, as above pointed out, so that the grinding operation continues until a rotating gauge, of the type disclosed in the McDonough Reissue Patent No. 16,141, enters the workpiece to procure cessation of the grinding operation when the workpiece reaches the desired finished size. As fully disclosed in said McDonough patent, a gauge, not shown, is intermittently urged against the end of the workpiece and is arranged to enter within the bore of the workpiece with a longitudinal movement directly as the workpiece reaches the predetermined finished size, thereby to separate the wheel and work piece. The longitudinal movement of the gauge into the bore of the workpiece trips a latch 77, Fig. 14, and allows a pivotally mounted arm 78 carrying a gauge contact 80 to swing, thereby to bring said contact into engagement with a stationary contact 81, said contacts being normally held in spaced relation by the latch. Engagement of the gauge contacts is arranged to procure an extended movement of the grinding wheel carriage to the right to separate the grind-

ing wheel from the workpiece in the following manner:—

The contact on the arm 78 is grounded at 82 and the contact 81 is connected by a lead 83 to one terminal of an electromagnet 84, the other terminal of said magnet being connected by a lead 85 to the lead 54 to the generator 55. Engagement of the contacts thus completes a circuit through magnet 84, thereby energizing the magnet and causing attraction of an armature member 86 pivotally mounted on the same shaft 58 that forms the pivotal mounting for the armature 57. Attraction of the armature 86 procures a counterclockwise movement of an upwardly extending arm 87 and a depending arm 88 both integral with said armature. Movement of the upwardly extending arm 87 allows the carriage to move beyond the normal reciprocatory position in an extended movement to the right, and is effected in the following manner:—

The upper end of the arm 87 is normally directly beneath the path of travel of the left hand table dog 7, Fig. 2, which is pivotally mounted upon the carrying block 73 and normally depends by gravity in the position shown. Raising of the end of the arm 87 engages and lifts the dog 7 so that on the subsequent right hand movement of the carriage 1 the dog is lifted entirely clear of the reversing lever 12 and the pilot valve is, therefore, not shifted to the left whereby the carriage continues outwardly to the right carrying the grinding wheel to rest position.

The grinding wheel is brought to rest at the end of its outward movement at the completion of a grinding operation to permit a workloading operation to take place. As shown in Fig. 15, a valve 89 which is in the fluid pressure line 36 between the main valve 14 and the right hand end of the cylinder 5 has an upwardly extending stem 90 and is normally urged into the full open position of Fig. 15 by a spring not shown. When the carriage 1 travels to the right to separate the grinding wheel from the workpiece, an abutment, not shown, on the carriage engages a lever, not shown, on the stem 90, thereby rotating the valve 89 and locking the fluid in the right hand end of the cylinder 5, so that the carriage can thereafter move no further to the right. It will be seen, however, that whenever the main valve 14 is moved to the right hand position, fluid can pass to the right hand end of the cylinder 5 by way of the passage 91 which by-passes the valve 89, said by-pass being closed when the valve 14 is moved to the left.

Movement of the armature 86 also operates a valve which causes the grinding wheel to be moved laterally away from the workpiece and thereby to be repositioned for entry, during the grinding of a subsequent workpiece, into the unfinished bore thereof. Referring to Fig. 15, the end of the depending arm 88 engages a groove in the valve 92 which moves in a casing 93 provided with an inlet port 94 connected to the pressure side of the pump by a pipe 95 and an outlet port which is connected to a cylinder 96 by a pipe line 97. Said cylinder has a piston 98 slideable therein which operates to rotate the cross-feed screw shaft 37 counterclockwise by mechanism disclosed in the above cited Patent No. 1,830,358 and not of itself a part of the present invention. This counterclockwise rotation withdraws the cam 40 from engagement with the adjusting screw 42 into a position for the subsequent energization of the magnet 53 during the succeeding grinding operation and places the grinding wheel in the original po-

sition in readiness for another grinding operation.

During the outward movement of the grinding wheel carriage to rest position, rotation of the workhead 3 is stopped in order to permit the re-

5 loading of the workholding member. As shown in Fig. 15, a valve casing 100 has a pressure port 101 connected by a pipe line 102 to the pressure side of the pump, an outlet port 103 which connects to a cylinder 103' and an exhaust port 104.

10 A valve member 105 which normally closes the pressure port is adapted to be rotated during and in response to the outward movement of the carriage to open the pressure port and to close the exhaust port, thereby to permit fluid under pres-

15 sure to flow directly to the cylinder 103', actuating a piston 106 slidably in the cylinder 103' which operates in any well known manner to stop rotation of the workholding member. The mechanism for actuating the valve 105 is fully disclosed in the

20 above cited Patent No. 1,914,995.

As movement of the carriage to the right is discontinued by rotation of the valve member 89, the right hand end of the piston rod 6, Fig. 1, engages and moves a valve member 107 to the

25 right, thereby to set in operation the mechanism by which the completed workpiece is removed from the workholding member, and an unground workpiece inserted therein. Referring to Fig. 15, the valve member 107 is slidably mounted in a

30 valve casing 108 which latter has an inlet 110 connected by a pipe line 111 to the pipe line 102 which connects to the pressure side of the pump. The casing further has an outlet port 112 connected to the pipe line 113 and an ex-

35 haust port 114, the valve 107 being normally maintained in the position of Fig. 15 by a spring 115 so that the inlet port in the casing thereof is normally closed. Movement of the valve to the right, in response to movement of the car-

40 riage, as above pointed out, provides fluid connection between the inlet port 110 and the outlet port 112 which sets in operation the workholding instrumentalities. In order to more clearly understand the invention, the operating mechanism will be described before the function of the hydraulic actuating mechanism therefor.

The workloading mechanism, indicated generally at 116, Fig. 1, is mounted on the right hand end of the workhead directly over the workholding member or chuck and is supported on the workhead by bolts 117 which engage through longitudinal slots 118 in said workloading mechanism thereby to permit adjustment of the work-

50 loading member relative to the chuck. The mechanism shown is arranged to be used with a delivery chute of the type shown and described in the above cited Highberg Patent No. 1,840,841, which is not of itself the invention in the present application, said chute being arranged to be connected to the upper end of the work-hopper 119

55 as will hereinafter more clearly appear. The support for the workloading mechanism comprises a chuck guard 120 having a substantially plane top which provides a wide transverse portion 121 and a portion 122 extending to the left therefrom, the latter supporting the actuating mechanism for the loading mechanism.

The first operation of the workloading mechanism is to remove the completed workpiece from the chuck which holds the workpiece in the workhead 3 by mechanism which is best shown in Fig. 7. A vertical bearing is provided in the forward portion of the chuck guard and supports a shaft 123 pivotally therein, the lower end of said shaft being provided with a work transfer arm 124 fix-

edly mounted thereon, the outer end of which carries spring members 125 of the type shown in the above cited Highberg application for engaging within the bore of the completed workpiece to support said workpiece. During the 80 grinding operation, the arm 124 normally extends forwardly from the shaft 123 toward the front of the machine as shown in Fig. 1. When the workloading mechanism is started in operation, the shaft 123 is rotated substantially through a half circle, thereby swinging the arm 124 toward the right and into the chuck so that the spring members 125 engage within the bore of the workpiece and impinge the workpiece thereon; said arm is then returned substantially 85 to the original position carrying therewith the completed workpiece, the latter being removed from the spring members during the return movement by mechanism carried on the lower end of the work-hopper 119, Fig. 7, as will hereinafter 90 appear.

Rotation of the shaft 123 is procured in response to rotation of a cam 126, Fig. 3, which is operated by fluid pressure as will be pointed out, movement of said cam being at first counterclockwise through substantially a complete revolution and subsequently clockwise to the original position. A cam groove 127 having substantially the configuration shown in Fig. 5 is engaged by a roller 128, Fig. 4, on one end of a bell crank lever 130 pivotally mounted on a stud 131 on the portion 121 of the chuck guard, the other end 132 of said bell crank lever being formed as a segmental gear which engages with a pinion 133 rigidly mounted on the upper end of the 100 vertical shaft 123. It will thus be seen that rotation of the cam 126 counterclockwise will swing the work-transfer arm 124 through its entire movement once and subsequent return of the cam to its original position will repeat the swing- 105 movement of the arm 124, the first swinging movement operating to remove the completed workpiece from the chuck, as above set out; the second swinging movement carrying an unground workpiece into chucking position and 110 maintaining it until the chuck is actuated to clamp the workpiece securely therein. In order to permit the removal of the completed workpiece, the clamping members of the chuck are released, said release being effected by the same 115 rotation of the cam that operates the work-trans- 120 fer arm in the following manner:—

Referring to Figs. 4 and 5, the cam is provided with a cam groove 134 which is provided with laterally spaced projections 135 and 136 on opposite sides thereof. A lever 137 pivotally mounted on a stud 138 on the portion 121 of the chuck guard carries a roller 139 on one end thereof for engagement in the cam groove 134. The other end of the lever is provided with a handle 140 and 130 a roller 141 between the pivotal point 138 and the handle, the roller 141 engaging a grooved portion in a slidably valve 142, Figs. 4 and 15. During the counterclockwise rotation of the cam, the lever 137, which is normally in the position shown 135 in Fig. 4, is engaged by the projection 135 and rocked clockwise as viewed in Fig. 4, thereby moving the valve 142 toward the front of the machine. Movement of the valve 142 is arranged to operate the chuck to release the clamping members in 140 the following manner:—

Referring to Fig. 15, the valve is shown in the normal position in which the chuck is closed, that is, the workpiece is clamped within the chuck. The casing 143 for the valve 142 is provided with 150

an inlet port 143' which is connected to the fluid pressure line by pipes 144, 111 and 102, and is also provided with ports 145 and 146 connected to opposite sides of a piston, not shown, slidably mounted in a cylinder, also not shown, which operates to open or close the chuck and an exhaust port 147. With the valve in the position shown, fluid connection is provided between the inlet port 143' and the port 145 which connects to one end of the cylinder by which the chuck is actuated, thereby maintaining the chuck in closed position, the other end of the cylinder being in fluid connection with the exhaust port 147 through port 146. Movement of the valve 142 in response to rotation of the cam establishes fluid connection between the inlet port 143' and the opposite end of the cylinder through port 146, thereby actuating the draw rod of the chuck to open said chuck and release the workpiece. When the cam 126 is returned to its original position by clockwise rotation, the projection 136 engages the roller 139 on the end of the lever 137 and returns the valve 142 to its original position at which time the draw rod of the chuck is again actuated, thereby to clamp the unground workpiece which has been inserted into the chuck. It will be noted that the cam groove 134 is of greater width than the roller received therein, thereby permitting manual operation of the chuck by movement of the handle 140 when desired. The piston and cylinder arrangement for actuation of the chuck is well known, and is disclosed in the above cited Highborg Patent No. 1,840,841.

During the second swinging movement of the workloading arm from the position shown in Fig. 7, the spring members 125 mounted on the end of the arm are adapted to engage unground workpieces and carry them into clamping position within the chuck. From a consideration of Fig. 40, it will be seen that the end of the arm 124 carrying the spring members 125, passes through the lower end of the hopper 119, the latter being more clearly shown in Figs. 10, 11 and 12. The spring members on the end of the arm are adapted to engage workpieces held in the lower end of the hopper and carry them from said hopper, where they are releasably maintained, into chucking position, the workpieces being supplied to the lower end of the hopper in the following manner:—

The hopper comprises spaced parallel guide members 148 and 149, each guide member having recesses 150 and 151 therein, Fig. 7, for guiding the workpieces, the construction shown being arranged to support two workpieces in a position for engagement by the workloading arm, both workpieces being transferred to the chuck at the same time, and the latter being adapted to receive both of said workpieces to maintain them simultaneously in grinding position therein. As will be apparent from Fig. 7, the workpieces are moved downwardly toward the lower end of the hopper by gravity, the column or stack of workpieces being prevented from resting on the piece about to be transferred by mechanism actuated by the loading arm 124 as will hereinafter appear. At the lower end of the work hopper, referring to Figs. 7 and 10, separating rails 152 and 153 for maintaining the workpieces in spaced relation and end rails 154 and 155 are pivotally mounted at 156 and 157, for swinging movement out of engagement with the workpieces, as the work-transfer arm is actuated through the loading movement. Each of these pivotally mounted members carries an outwardly projecting arm 158

which is engaged by one end of a spring member 159, the other end of which is attached to a pin 160 mounted on the stationary part of the hopper. Adjustable stop members 161 and 162 are provided in lugs 163 mounted on the stationary part of the hopper to maintain the rails in the position shown in Fig. 10. A stop member 164 is carried on the bottom end of each guide rail 148 and 149 to prevent the workpieces from passing out through the bottom of the channels 185 therein. Each of the pivotally mounted rails is bevelled as shown in Fig. 7 at 152', so that as the transfer arm engages the workpieces, and forces them rearwardly of the hopper, the pivotally mounted rails may swing out of the way 190 of the workpieces, in response to the rearward movement thereof, thereby to permit movement of said workpieces from the end of the hopper. It will be apparent that the rails are returned to the position of Fig. 10 by the springs 159 as 195 soon as the workpieces carried on the arm have been moved beyond the end of the hopper during the loading movement of the transfer arm. Accordingly, the end rails 154 and 155 are in a position during the swinging of the transfer arm 100 in a subsequent workloading operation to engage with the sides of the completed workpieces carried by the transfer arm during the removal of said completed workpieces from the chuck, thereby to remove said completed workpieces from the 105 spring member, the completed workpieces dropping into a tray or container not shown. It will be noted that this stripping of the workpieces from the work-transfer arm occurs as the arm is swung away from the chuck after having im- 110 pinged the finished workpieces on the spring members, as above pointed out.

Since the removal of the completed workpieces from the chuck occurs during a workloading operation prior to the insertion of unground 115 workpieces, the hopper is arranged to maintain the unground workpieces away from the lower end of the hopper during the first swinging movement of the transfer arm in order to permit said arm to swing freely, thereby to carry the 120 spring members on said arm into engagement with the completed workpieces. The unground workpieces to be loaded in the chuck are arranged to fall by gravity into the lower end of the hopper at the end of the first swinging move- 125 ment of the transfer arm and to accomplish this, mechanism is provided which controls the position of the unground workpieces and which is actuated by movement of the transfer arm in the following manner:—

Referring to Figs. 7 and 13, spaced lugs 165 and 166 are adapted to be inserted in slots 167 and 168 formed in the guide member 148 and are adapted to be moved alternately into and out of workpiece engaging position in order to permit 135 two workpieces to drop into position for engagement by the work-transfer arm and to maintain the remaining workpieces out of engagement with said first workpieces, thereby preventing the entire column of workpieces from resting on the 140 pieces to be transferred to the chuck. The vertical spacing of the lugs 165 and 166 is such that when the stack of workpieces is resting on the lower lug 166, the upper lug may move between the workpieces resting on the lower lug and the 145 next succeeding workpieces thereabove, whereby the upper lug 165 will support the stack of workpieces when the lower lug 166 is withdrawn, permitting only the lowermost workpieces in the stack to drop into workloading position. Simi- 150

larly, when the lower lug is in a position to prevent the workpieces from moving into the bottom of the hopper, the upper lug may be removed, thereby to permit the column of workpieces to move down by gravity to rest on the lower lug 166; said upper lug may thereafter be returned for engagement between the lowermost workpieces resting on the lower lug and the next succeeding workpieces above. It will be noted that there are two columns of workpieces in parallel relation in the hopper, so that the lowermost workpieces in the two columns are loaded and controlled as a unit.

The lugs 165 and 166 are withdrawn and returned to work-engaging position in response to movement of the work-transfer arm, the upper and lower lugs 165 and 166 being provided respectively with circular rods 173 and 174 extending therefrom. A bracket 175 which is mounted upon the front of the chuck guard 120 by bolts 176 and 177 provides bearings 178 and 179 for said rods in an arm 180 integral with said bracket. Movement of the rod 173 in its bearing 178 is limited by a collar 181 locked in position on said rod by a set screw 182 on one side of said bearing and a similar collar 183 on the opposite side of said bearing locked on said rod by a set screw 184, said latter collar providing a stud 185 forming a pivotal support for an arm 186 by which said rod is actuated. A stud bolt 187 mounted in a hub 188 formed on the bracket 175 provides a bearing surface on which a member 190 is slidably mounted, said member having an arm 191 similar to the arm 180, said arm 191 providing bearings for the rods 173 and 174, the latter rod 174 being held against sliding movement in said arm by a set screw 192. The member 190 has a stud 193 thereon which engages an elongated slot 194 in the arm 186, providing a pivotal support for said arm. The arm 186 depends below the elongated slot 194 and is provided with a boss 195 which receives a screw threaded member 196 adjustably held therein by adjusting nuts 197 and 198. The end of the screw threaded member 196 carries a rigidly mounted depending arm 200 thereon, the lower end of said arm carrying an adjustable stud 201 held in adjusted position by adjusting nuts 202 and 203. A pin 204 formed on said boss 195 is engaged by one end of a spring 205, the other end of which is carried by a pin 206, Fig. 7, mounted on the hopper, the spring tending to urge the lower end of said arm 186 toward the right, thereby to urge said member 190 into engagement with the hub 188.

In the normal position of the arm 186 in which the arm 124 is rotated counterclockwise from the position shown in Figs. 7 and 13, and out of engagement with stud 201, the lower lug 166 is in position to prevent workpieces from passing down through the hopper, and the upper lug 165 is withdrawn from work-engaging position. It will be apparent that as the stud 201 is engaged by the work-transfer arm, Fig. 7, the arm 186 is rocked clockwise from normal position against the action of the spring 205 into the position shown in Figs. 7 and 13.

From a consideration of Fig. 5, it will be apparent that the work-transfer arm, which is actuated by movement of the cam 126, is rotated beyond the normal position of said arm at the end of the first swinging movement, that is, at the end of the movement for removing the completed workpiece, whereby said arm engages the stud 201 and actuates the work-feeding mechanism to allow an unground workpiece to drop into posi-

tion in the lower end of the hopper between the unloading movement and the loading movement of the arm 124.

In order to understand the operation of the lugs 165 and 166, the work-transfer arm operates briefly as follows:—The work-transfer arm starts from normal or rest position, that is, a position somewhat beyond the position shown in Fig. 7, such that the arm is out of engagement with the stud 201 when said stud is in the normal position. The work-transfer arm 124 is first rotated counterclockwise in response to rotation of cam 126 carrying the spring members on the end thereof through the lower end of the hopper, the latter having no workpieces in the lower end thereof during this movement, said spring members being ultimately brought into engagement with the bore of the completed workpieces in the chuck. The jaw members of the chuck having been previously released, the work-transfer arm carrying the workpieces thereon, is then swung clockwise to swing the outer end thereof back between the lower ends of the guide members 148 and 149, the completed workpieces being withdrawn from the spring members, by engagement of the plates 154 and 155 with the workpieces. During this clockwise rotation of the work-transfer arm, by reason of the shape of the actuating cam 126, the arm 124 is carried beyond the normal position of rest into the position shown in Fig. 7, in order to engage the adjusting stud 201, thereby rocking the arm 186 clockwise to allow unground workpieces to drop into the lower end of the hopper for engagement with the spring members 125 during the subsequent counterclockwise rotation of the work-transfer arm during the loading movement. Said arm 124, during its second counterclockwise rotation, engages said workpieces and carries them out of the hopper against the holding action of the rails 152, 153, 154 and 155 into chucking position within the workholder, after which the arm rotates clockwise to withdraw said spring members from the workpieces, said arm returning to its original position of rest, out of engagement with stud 201.

The operation of the lugs 165 and 166 in response to engagement of the stud 201 by the work-transfer arm is as follows:—As above pointed out, the arm 186 is normally urged counterclockwise by the action of the spring 205 to bring the collar 181 into engagement with the arm 180, thereby withdrawing the lug 165 from work-engaging position and urging the lug 166 into work-engaging position in response to sliding movement of the member 190 toward the right. It will thus be seen that the normal position of the arm 186 is such that the lower lug 166 is in work-engaging position, the member 190 resting against the hub 188, and the upper lug 165 is withdrawn from work-engaging position. From this normal position, the lugs are actuated by engagement of the work-transfer arm with the stud 201 at the end of the first swinging movement of said arm. Referring especially to Fig. 13, the counterclockwise movement of the work-transfer arm moves the stud 201 to the left, thereby urging the arm 186 clockwise. The position of the spring 205 tends to hold the slideable member 190 toward the right so that the lug 165 is actuated to the right and into work-engaging position before the slideable member 190 is actuated to the left, the stud 193 on the slideable member acting as a pivot for the arm 186. When the lug 165 is in work-engaging position, the collar 183 engages the arm 180 so that continued

movement of the stud 201 to the left carries the 5 workpieces drop into the bottom of the hopper, the remainder of the stack being supported by lug 165. The subsequent swinging movement of the work-transfer arm counterclockwise, as above pointed out, permits the stud 201 to return to its 10 normal position, whereby the member 190 is urged to the right to move the lug 166 again into work-engaging position and, when the bearing member 190 comes in contact with the hub 188, continued rocking of the arm 186 by said spring 15 205 withdraws the lug 165 from work-engaging position, thereby returning the parts to the original position.

Movement of the lugs 165 and 166 accordingly occurs in the following order beginning from the 20 normal position in which the lower lug 166 is in work-engaging position and the upper lug is withdrawn therefrom. Considering the workpieces in one of the columns, in response to movement of the work-transfer arm, the upper 25 lug is urged into work-engaging position to support all the workpieces except the lowermost one which is between lugs 165 and 166, after which the lower lug is withdrawn, thereby allowing said lowermost workpiece to drop into the lower end 30 of the hopper for engagement by the spring members on the end of the work-transfer arm. Subsequently the lower lug is returned to work-engaging position to prevent movement of the stack into the bottom of the hopper after which 35 the upper lug is withdrawn therefrom in response to the return movement of the arm 186 to normal position to allow the stack of workpieces to drop from the position above the upper lug into position against the lower lug where they are supported in readiness for the delivery of the lowermost workpiece to the lower end of the hopper during the succeeding workpiece loading operation.

As above pointed out, movements of the work-loading mechanism occur at the end of a grinding operation and are initiated by engagement of the valve 107 with the end of the piston rod 6 during the runout of the machine to rest position. Referring to Fig. 15, the outlet port 112 of the 45 valve 107 is connected by the pipe 113 to spaced inlet ports 208 and 210 in a casing 211 for a valve 212, said casing being provided with spaced outlet ports 213 and 214 which are connected to inlet ports 215 and 216 at opposite ends of a valve casing 217 by pipes 218 and 220 respectively. The casing 211 is provided with an enlarged bore 221, Fig. 9, at one end thereof to receive the enlarged end 222 of the valve 212, arranged in such a manner that fluid under pressure entering the port 208 will urge the valve 212 toward the left. In the normal position of the valve, as shown in Figs. 9 and 15, fluid connection is provided between the inlet port 210 and the outlet port 213 so that when fluid under pressure passes through the pipe 113, 50 it is carried directly through the casing 211 into the left hand end of the casing 217, the right hand end of the casing being connected to an exhaust outlet 223 through the pipe 220. In this position of the valve 212, the fluid under pressure 55 passing through casing 211, actuates a piston 224 slidable in the casing 217 toward the right, and procures rotation of the cam member 126 in the 60 following manner:—

Referring to Figs. 3 and 8, it will be seen that 75 the piston 224 is provided with a piston rod 225,

the projecting end of which is enlarged and formed to provide a rack member 226. As shown in Fig. 3, the casing 217 is mounted on the extending portion 122 of the chuck guard 120 with the piston rod extending toward the right, as 80 seen from the front of the machine, the outer end of said piston rod 225 being supported in a bearing 227 mounted on the portion 121 of the chuck guard. Said bearing provides a set screw 228 engaging a groove 229 in the piston rod, thereby supporting the rack 226 against rotation. The cam 126 is supported at opposite ends in bearings 230, formed on the chuck guard 120, and is provided with a pinion 231 for engagement with the rack 226. Movement of the piston toward the 85 right, in response to movement of valve 107, 90 procures rotation of the cam counterclockwise, thereby procuring the first swinging movement of the workloading arm through swinging movement of the gear segment 132 to procure the unloading 95 of the completed workpiece from the workholding member.

As the piston 224 reaches the right hand end of its stroke, the flow of fluid under pressure to the casing 217 carrying said piston is directed 100 to the right hand end thereof (Fig. 15) to return said piston to the left hand end of the cylinder, thereby rotating the cam 126 clockwise to complete the operation of the workloading mechanism, that is, to transport an unground work- 105 piece from the lower end of the hopper into work-clamping position within the chuck. From a consideration of Fig. 15, it will be apparent that fluid entering the port 208 tends to urge the valve member 212 to the right in which position 110 pressure fluid from the pump will be admitted to the right hand end of the casing 217. Movement of the valve 212 does not occur, however, until the piston 224 has reached the right hand end of travel, the valve 212 being held against 115 movement to the right in the following manner:—

Referring particularly to Figs. 4, 5 and 9, the valve 212 has an extension thereof, provided with a groove 232 which receives one end of a bell 120 crank lever 233, the latter being pivotally mounted on a stud 234 on the extending portion 122 of the chuck guard, the other end of said lever having a roller 235 thereon which engages in a cam groove 236 in said cam. The cam groove 125 comprises two parallel circular grooves 237 and 238 interconnected at opposite ends. During the initial movement of the cam, the roller 235 is in the circular groove 237, thereby preventing rocking of the bell crank lever 233 and maintaining 130 the valve 212 in its extreme right hand position. At the end of the counter clockwise rotation of the cam, when the piston 224 is in the extreme 135 right hand position, the roller 235 is allowed to move from groove 237 to groove 238 at the point where said grooves are interconnected, thereby permitting the valve 212 to move to the left in response to the fluid under pressure passing into port 208. Movement of the valve 212 provides fluid connection from the pump to the right hand 140 end of the casing 217 and connects the left hand end of said casing to the exhaust port 223, whereby the piston 224 is urged to the left rotating the cam clockwise to return said cam to its original position. During the latter clockwise rotation of the cam, the work-transfer arm is swung through its loading movement, thereby carrying the unground workpiece into work-chucking position.

As the cam 126 is returned to its original po- 150

sition, the unground workpiece now having been placed in the workholding member, the workloading operation being thus completed, the carriage 1 is started from rest position, carrying the 5 grinding wheel to the left and into operative relation with the unground workpiece, in the following manner:—

Referring to Figs. 8 and 15, the casing 217 for the piston 224 is provided with a channel 240 from the bore for said piston to a cylindrical bore 241 in the casing 217; said bore 241 receives a slideable valve member 242, the latter being normally urged into extreme right hand position by a spring member 243 which engages at one end 10 with the cylinder head 244 provided for said casing and at the other end with an enlarged flange 245 on the end of said valve. The cylindrical bore 241 has an outlet port 246 connected by a pipe 247 to the right hand end of the casing for 15 the pilot valve 13 and an exhaust port 248, fluid connection being provided between said outlet port 246 and the exhaust port 248 in the normal position of the valve as shown in Fig. 15, thereby 20 normally having no effect on the movement of the pilot valve 13. The valve 242 is urged to the left at the completion of the workloading operation to establish fluid connection from the channel 240 to the outlet opening, thereby admitting fluid under pressure to the right hand 25 end of the pilot valve 13, this movement occurring just before the piston 224 reaches normal position on the return stroke. As shown in Figs. 30 4 and 8, a link 250 is connected to the bell crank lever 233 at one end and is provided on the opposite end with a roller 251 which engages in a groove 252 provided by the flange 245 on the end of the valve 242. The latter end of the link also carries an upstanding stud 253 which engages with a stop member 254 mounted on the extension 35 of the piston rod 225 for the piston 224. Swinging movement of the bell crank lever 233, during the operation of the workloading mechanism as above pointed out, actuates the link to place the stud 253 in a position for engagement 40 with the stop member 254 during the left hand movement of the piston 224 to its original position (said movement being to the right in Fig. 3), thereby moving the valve 242 to the left, Fig. 15, and providing fluid connection through the 45 channel 240 to the outlet port 246 and closing the exhaust port 248, whereby fluid under pressure is admitted to the right hand end of the pilot valve, thereby to actuate said valve and 50 initiate the return movement of the grinding wheel carriage into operative position.

As movement of the table or carriage to the left is begun, the end of the piston rod 6 is withdrawn from contact with the valve 107, thereby permitting said valve to be urged to the left in response to the spring 115 so that the inlet port 55 in the casing 108 is closed, the exhaust port being at that time opened to relieve the fluid pressure in the pipe line 113. This relieves the pressure in the bore 221 of the casing 211, thereby permitting the valve 212 therein to return to the right into its original position under the influence of a spring 255, Fig. 9, which engages between the end of said casing and a flange 256 on said valve. This movement places the valve in a position 60 to permit a subsequent workloading operation to take place at the completion of a subsequent grinding operation.

During the movement of the valve 212 to the right at the end of the loading operation, the bell crank lever 233 is rocked, thereby placing the

roller in the end of the circular groove 237 to permit said bell crank lever to function during the succeeding workloading operation in holding the valve in desired position. In order to prevent the valve 212 from sliding to the left, Fig. 15, immediately as fluid under pressure is allowed to enter the enlarged bore 221 at the beginning of a workloading operation, a latch member is provided to hold the roller on the end of the bell crank lever 233 in the end of groove 237, thereby preventing swinging movement of the lever and accordingly holding the valve 212 in right hand position. Referring to Fig. 6, a latch member 257 is received within a recess 258 formed in the cam 126, said latch being pivotally mounted on a pin 260. The projecting end 261 of the latch extends into the groove connecting the grooves 237 and 238 at one end thereof and is normally held outward in roller engaging position by a spring 262 within the recess, outward movement of the latch 257 in response to said spring being limited by a projecting portion 263 of said lever which engages a portion of the cam. It will be seen that, as the bell crank lever swings, thereby to move the roller from the groove 238 into the groove 237 at the completion of a workloading operation, the latch is depressed to permit this swinging movement and is then urged outwardly to prevent rocking movement of the bell crank lever which would move the roller back into the groove 238, thereby holding the valve 212 to the right until the cam 126 has been rotated counterclockwise during the workloading operation, as above pointed out.

Swinging movement of the bell crank lever 233, at the end of the workloading operation, withdraws the stud 253 from engagement with the stop member 254, thereby permitting the valve 242 to return to original position in readiness to perform its function during the succeeding loading operation. Return of valve 242 to original position connects the right hand end of the pilot valve 13 to the exhaust, so that the pilot valve may be actuated during the succeeding grinding operation.

As the pilot valve 13 is urged to the left, in response to movement of the valve 242 as above pointed out, the main valve 14 is actuated to the right, thereby opening the passage 91 which bypasses the valve 89, whereby fluid may flow from the pump to the right hand end of the cylinder 5, thereby urging the carriage to the left carrying the grinding wheel into operative relation with the workpiece to procure a grinding operation. As the carriage is moved, the abutment which engages the upwardly extending lever on the stem 90 is withdrawn from engagement therewith, thereby allowing the valve 89 to return to original open position, and during the same movement of the table or carriage into operative position, an arm 264 pivotally mounted on the carrying block 70 on the front of the carriage engages a lug 265 on the pivotally mounted switch 50, thereby returning said switch to its original position for subsequent functioning during a succeeding grinding operation.

To summarize briefly the operation of the machine, the pilot valve 13 is moved to the left, thereby starting the carriage from rest position toward the left to bring the grinding wheel carried by said carriage into operative relation with a workpiece in the workholding member, movement of the pilot valve being effected either manually or in response to fluid pressure entering the right hand end of the casing 16. ing is continued with the grinding wheel in operative relation to the workpiece until the workpiece is ground nearly to a finished size when a dressing operation is performed on the wheel after which grinding is again resumed until a gauge 5 enters the bore of the workpiece just as the workpiece reaches the predetermined size, thereby procuring separation of the grinding wheel carriage from the workholding member to permit the workloading mechanism to operate. During the 10 separation of the grinding wheel and workloading member, cross-feed movement of the workholding member relative to the grinding wheel is retracted in order to place the members in the 15 original position in readiness for a subsequent grinding operation. The grinding wheel carriage is carried away from the workpiece and is brought to rest by the rotation of valve 89, thus locking fluid in the right hand end of the cylinder 5 and preventing movement of the 20 carriage to the right, the valve 13 being in the right hand position in which the normal movement of the carriage is toward the right. Just as the carriage is brought to rest, the right hand end of the piston rod 6 engages a valve 107 thereby admitting fluid under pressure through 25 the valve 212 and into the left hand end of casting 217, thereby actuating the piston 224 to the right, rotating the cam 126 counterclockwise to swing the workloading arm 124 from the normal 30 position around through the lower end of the hopper (there being no workpieces therein at this time) and into the bore of the completed workpiece. The same counterclockwise movement of the cam 126 moves the valve 142 through 35 the lever 137 thereby releasing the clamping members within the workholding member. The workpiece now being impaled on the spring members 125, rotation of the arm clockwise withdraws 40 the workpiece from the workholding member and as the arm passes through the lower end of the hopper during this return movement, the workpiece is stripped from said spring members. The 45 above swinging movement of the workloading arm occurs in response to and during the right hand movement of the piston 224, and as the piston reaches its right hand end of stroke, the valve 212 is actuated in response to fluid under pressure to admit fluid to the right hand end of the cylinder 217, thereby to actuate the piston 50 224 to the left. This return movement of the piston actuated the workloading arm through its loading operation carrying a workpiece from the lower end of the hopper into the workholding member. The workholding member is then 55 closed in response to movement of valve 142 while the workpiece is supported within the workholding member by the workloading arm and subsequent return movement of the workloading arm withdraws the spring members 125 from the 60 bore of the workpiece. The unground workpieces are supplied to the lower end of the hopper before the workloading arm is swung through the loading movement, said arm being swung at the 65 end of the unloading operation into engagement with a stud 201, thereby withdrawing the lug 166 from the recesses 150 and 151 to allow a workpiece to drop into the bottom of the hopper.

Just before the piston 224 reaches its original 70 position in the left hand end of the casing 217, a stop carried by the piston rod 225 for said piston actuates the valve 242 to the left, thereby permitting fluid under pressure to pass through said valve 242 into the right hand end of the casing 16, thereby actuating the pilot valve 13 to the left to

start the grinding wheel carriage in toward the left to carry the grinding wheel into operative relation with the unground workpiece which has now been substituted for the completed workpiece. As this return movement of the carriage occurs, 80 the valve 107 is allowed to return to its closed position, whereby the workloading instrumentalities are returned to the original position in readiness for a subsequent workloading operation.

It will be apparent that, in the operation of the machine, the workloading instrumentalities will not function until the grinding wheel carriage has been carried to its extreme right hand position and brought to rest at which time the workloading instrumentalities are set in operation 85 in response to the movement of the carriage. The workloading instrumentalities having been set in operation, the continued operation thereof is independent of the remainder of the machine, the entire operation of removing the completed workpiece and inserting the new workpiece occurring 90 in response to fluid under pressure. After the workloading is completed, the grinding wheel is returned to operative relation with the unground workpiece in response to mechanism controlled 95 by the workloading instrumentalities.

I claim,

1. In a grinding machine, a grinding wheel and a workholder in operative relation thereto, means to procure separation of said wheel from said member at the completion of a grinding operation, workloading means, means responsive to said separation to initiate the operation of said workloading means, and means actuated by said workloading means to return the wheel to operative position relative to the workholder.

2. In a grinding machine, a grinding member and a workholding member in operative relation thereto, means to procure separation of said members at the completion of a grinding operation, workloading means for the removal of a completed workpiece from the workholding member and the insertion of an unground workpiece therein, means to initiate the operation of said workloading means in response to the separation 120 of said members, and means set in operation after the unground workpiece has been inserted in the workholding member to return said members to operative position.

3. The combination with a workholder having 125 clamping means adapted to clamp a workpiece, of a workloading mechanism comprising means to open and close said clamping means, and means to remove a finished workpiece from said workholder and to insert another workpiece therein 130 while said clamping means are open, said workloading mechanism being actuated by fluid under pressure.

4. The combination with a workholder having 135 clamping members adapted to clamp a workpiece, of a workloading mechanism comprising means to open and close said clamping members, a work carrier, and means to actuate said work carrier to remove a completed workpiece from said workholder and to insert another workpiece 140 while said clamping means are open, said last means also actuating the means for opening and closing the clamping members.

5. The combination with a workholder having 145 clamping members adapted to clamp a workpiece, of a workloading mechanism comprising means to open and close said clamping members, work carrying means to remove a workpiece from said workholder and to insert another workpiece 150 therein, means actuated by said work carrying

- means to place workpieces successively in a position for engagement by said carrying means for insertion in the workholder, and fluid pressure means to actuate said workloading mechanism.
5. 6. The combination with a workholder having clamping members adapted to clamp a workpiece, of a workloading mechanism comprising means to open and close said clamping members, work carrying means to remove a workpiece from said workholder and to insert another workpiece therein, means actuated by said work carrying means to place successive workpieces in position for engagement by said carrying means for insertion in the workholder, and means to actuate said workloading mechanism.
10. 7. In a machine of the class described, a workholding member adapted to clamp a workpiece therein, and a workloading mechanism comprising means to release a workpiece from said workholding member, means to remove a workpiece from said member and to insert another workpiece therein, and means thereafter to clamp the latter workpiece in said workholding means, means to set said workloading mechanism in operation, said workloading mechanism being automatically carried through an entire workloading operation after having been set in operation.
15. 8. In a grinding machine adapted for the reduction of successive workpieces to a predetermined size, a grinding member, a workholding member having a workpiece secured therein, means to procure axial separation of said members when the work piece has been ground to a predetermined size, workloading mechanism for the removal of the completed workpiece from the workholding member and the insertion of an unground workpiece therein, said mechanism being set in operation in response to the separation of said members, and means to return said members into operative relation after the unground workpiece has been inserted in the workholding member.
20. 9. In a grinding machine adapted for the reduction of successive workpieces to a predetermined size, a grinding member, a workholding member having a workpiece secured therein, means to procure a cross-feed movement between said members, means to procure axial separation when the workpiece being ground has reached the predetermined size, means responsive to said separation to procure retraction of the cross-feed movement, workloading mechanism, means responsive to the separation of said members to initiate the operation of said workloading mechanism, and means to return said members into operative relation at the end of the workloading operation.
25. 10. A workloading mechanism for the automatic insertion of workpieces in a workholder, the latter comprising chucking means to release and to clamp a workpiece in the holder, said mechanism comprising a work carrier arranged to remove said workpiece from the holder and to insert another workpiece therein, means to remove a workpiece from the carrier and to maintain another workpiece in position for engagement with said carrier, and means for automatically actuating said chuck operating means and work carrier through an entire workloading operation.
30. 11. A workloading mechanism for the automatic insertion of workpieces in a workholder, the latter comprising chucking means to release and to clamp a workpiece held in the holder, said mechanism comprising a work carrier ar-
- ranged to remove said workpiece from the holder and to insert another workpiece therein, means to remove said workpiece from the carrier and to support the other workpiece in position for engagement with said carrier, and means to operate said chucking means, said workloading mechanism being actuated by fluid under pressure through an entire loading operation.
35. 12. In a grinding machine, a grinding member, a workholding member in operative relation thereto, means to procure separation of said members at the completion of a grinding operation, workloading means for the removal of a completed workpiece from the workholding member and the insertion of an unground workpiece therein, means to initiate the operation of said workloading means in response to the separation of said members, and means responsive to said workloading means, and actuated after the unground workpiece has been secured in the workholding member to return said members to operative position.
40. 13. In a machine of the class described, a workholding member adapted to clamp a workpiece therein, a workloading mechanism comprising means to release a workpiece from said workholding member, a work carrier for the removal of a workpiece from said member and the insertion of another workpiece therein, and means to clamp the latter workpiece in said workholding means, said workloading mechanism being automatically carried through an entire workloading operation.
45. 14. In a machine of the class described, a workholding member adapted to clamp a workpiece therein, a workloading mechanism comprising means to release a workpiece from said workholding member, a work carrier for the removal of a workpiece from said member and the insertion of another workpiece therein, means to clamp the latter workpiece in said workholding means, means actuated by said work carrier for positioning of the latter workpiece for engagement with the work carrier, and means to actuate the workloading mechanism whereby said mechanism is automatically actuated through an entire loading operation.
50. 15. In a grinding machine adapted for the reduction of successive workpieces to a predetermined size, a grinding member, a workholding member having a workpiece secured therein, means to procure a cross-feed movement between said members, means to procure axial separation when the workpiece being ground has reached the predetermined size, means responsive to said separation to procure retraction of the cross-feed movement, workloading mechanism comprising means to release and clamp workpieces in the workholding member, means to remove a workpiece from said member and insert another workpiece therein, means responsive to the separation of said members to set said workloading mechanism in operation, and means to return said members into operative relation at the end of the workloading operation.
55. 16. In a grinding machine adapted for the reduction of successive workpieces to a predetermined size, a grinding member, a workholding member having a workpiece secured therein, means to procure a cross-feed movement between said members, means to procure axial separation when the workpiece being ground has reached the predetermined size, means responsive to said separation to procure retraction of the cross-feed movement, workloading mechanism comprising

- means to release and clamp workpieces in the workholding member, means to remove a workpiece from said member and insert another workpiece therein, means responsive to the separation of said members to set said workloading mechanism in operation, and means to actuate said workloading mechanism through an entire workloading operation after having been set in operation, said last means procuring the return 10 of said members into operative relation at the close of the loading operation.
17. A workloading mechanism for the automatic insertion of workpieces in a workholder having chucking means to release or clamp a workpiece in said holder, said mechanism comprising a work carrier for the removal of a workpiece from and the insertion of a workpiece into said holder, means to remove a workpiece from said carrier and to place another workpiece thereon, means to operate said chucking means, and actuating means for the operation of the work carrier and said chuck operating means, said actuating means being adapted to operate the mechanism through an entire workloading 25 operation, and to bring the mechanism to a stop at the end of said operation.
18. The combination with a workholder having clamping means adapted to support a workpiece removably therein, of a workloading mechanism comprising means to remove a finished workpiece from said workholder and to insert another workpiece therein, said workloading mechanism being actuated directly by fluid under pressure.
19. The combination with a workholder having clamping members adapted to clamp a workpiece removably therein, of a workloading mechanism comprising work carrying means to remove a workpiece from said workholder and to insert another workpiece therein, means actuated by said work carrying means to place workpieces successively in a position for engagement by said carrying means for insertion in the workholder, and fluid pressure means to actuate said workloading mechanism.
20. In a machine of the class described, a work holding member, a workloading mechanism comprising means to remove a workpiece from said member and to insert another workpiece therein, and means to set said workloading mechanism in operation, said workloading mechanism being automatically carried through an entire workloading operation after having been set in operation.
21. In a machine of the class described, a workholding member, a workloading mechanism comprising means to remove a workpiece from said member and to insert another workpiece therein, means to set said workloading mechanism in operation, and fluid pressure means for automatically actuating said workloading mechanism through an entire workloading operation after said mechanism has been set in operation.
22. In a grinding machine adapted for the reduction of successive workpieces to a predetermined size, a grinding member, a workholding member having a workpiece secured therein, means to procure axial separation of said members when the workpiece has been ground to a predetermined size, workloading mechanism for the removal of the completed workpiece from the workholding member and the insertion of an unground workpiece therein, said mechanism being set in operation in response to the separation 70 of said members, and means responsive to the operation of the workloading mechanism to return said members into operative relation after the unground workpiece has been inserted in the workholding member.
23. In a grinding machine adapted for the reduction of successive workpieces to a predetermined size, a grinding member, a workholding member having a workpiece secured therein, means to procure a cross-feed movement between said members, means to procure axial separation when the workpiece being ground has reached the predetermined size, means responsive to said separation to procure retraction of the cross-feed movement, workloading mechanism, means responsive to the separation of said members to initiate the operation of said workloading mechanism, and means actuated by said workloading mechanism to procure return of said members into operative relation at the end of the workloading operation.
24. In a grinding machine adapted for the reduction of successive workpieces to a predetermined size, a grinding member, a workholding member having a workpiece secured therein, means to procure axial separation of said members when the workpiece has been ground to a predetermined size, workloading mechanism for the removal of the completed workpiece from the workholding member and the insertion of an unground workpiece therein, means responsive to the separation of said members to set said workholding mechanism in operation, fluid pressure means to actuate said workloading mechanism through a workloading operation, and means actuated by said workloading mechanism to return said members into operative relation at the completion of the workloading operation.
25. In a grinding machine adapted for the reduction of successive workpieces to a predetermined size, a grinding member, a workholding member having a workpiece secured therein, means to procure a cross-feed movement between said members, means to procure axial separation of said members when the workpiece being ground has reached a predetermined size, means responsive to said separation to procure retraction of cross-feed movement, workloading mechanism, means responsive to the separation of said members to initiate the operation of said workloading mechanism, fluid pressure means to 125 actuate said workloading mechanism, and means actuated by said workloading mechanism to procure return of said members into operative relation at the end of the workloading operation.
26. In a grinding machine, the combination with a grinding member, a workholding member in operative relation thereto, and means to procure separation of said members at the completion of a grinding operation, of workloading means for the removal of a completed workpiece 135 from the workholding member and the insertion of an unground workpiece therein, means to initiate the operation of said workloading means in response to the separation of said members, fluid pressure means to actuate said workloading means through a workloading operation, and means responsive to the movement of said workloading means and actuated after the unground workpiece has been secured in the workholding member to return said members to operative 145 position.
27. In a machine of the class described, a workholding member adapted to clamp a workpiece therein, a workloading mechanism comprising means to release a workpiece from said work-

- holding member, a work carrier for the removal of a workpiece from said member and the insertion of another workpiece therein, and means to clamp the latter workpiece in said workholding means, and fluid pressure means for automatically actuating said workloading mechanism through an entire workloading operation. 80
28. In a machine of the class described, a workholding member, a workloading mechanism comprising a work carrier for the removal of a workpiece from said member and the insertion of another workpiece therein, means actuated by said work carrier for positioning of the latter workpiece for engagement by said work carrier, and fluid pressure means to actuate the workloading mechanism through an entire workloading operation. 85
29. In a grinding machine adapted for the reduction of successive workpieces to a predetermined size, the combination with a grinding member, a workholding member having a workpiece secured therein, means to procure a cross-feed movement between said members, means to procure axial separation of said members when the workpiece reaches a predetermined size, and means responsive to said separation to procure retraction of the cross-feed movement, of a workloading mechanism comprising means to remove a workpiece from said member and insert another workpiece therein, means responsive to the separation of said members to set said workloading mechanism in operation, fluid pressure means to actuate said workloading mechanism through an entire workloading operation, and means actuated by said workloading mechanism to procure return of said members into operative relation at the end of the workloading operation. 90
30. In a grinding machine adapted for the reduction of successive workpieces to a predetermined size, the combination with a grinding member, a workholding member having a workpiece secured therein, means to procure a cross-feed movement between said members, means to procure axial separation of said members when the workpiece reaches a predetermined size, and means responsive to said separation to procure retraction of the cross-feed movement, of a workloading mechanism comprising means to remove a workpiece from said member and insert another workpiece therein, means responsive to the separation of said members to set said workloading mechanism in operation, fluid pressure means to actuate said workloading mechanism through an entire workloading operation, and means actuated by said workloading mechanism to procure return of said members into operative relation at the end of the workloading operation. 95
31. A workloading mechanism for the automatic insertion of workpieces in a workholder, the latter comprising chucking means to release and to clamp a workpiece in the workholder, said mechanism comprising a work carrier arranged to remove a completed workpiece from the holder and to insert another workpiece therein, means to remove said finished workpiece from the carrier and to maintain the other workpiece in position for engagement with said carrier, and fluid pressure means for actuating said workloading mechanism through an entire workloading operation and for bringing said mechanism to rest at the end of said operation. 100
32. In a grinding machine, a grinding member and a work-supporting member, means to procure a relative separation of said grinding member from a workpiece in said work-supporting member at the completion of a grinding operation, workloading means for procuring removal of a completed workpiece from the work-supporting member and the positioning of an unground workpiece therein, means to initiate the operation of said workloading means in response to the separation of said members, and means actuated by said workloading means to return the grinding member into operative relation to the workpiece in the work-supporting member. 105
33. In a grinding machine, a grinding member and a work-supporting member, means to procure a relative separation of said grinding member from a workpiece in said work-supporting member at the completion of a grinding operation, workloading means for procuring removal of a completed workpiece from the work-supporting member and the positioning of an unground workpiece therein, means to initiate the operation of said workloading means in response to the separation of said members, fluid pressure means for automatically actuating said workloading means through an entire operation, and means set in operation after the unground workpiece has been positioned in the work-supporting member for returning said grinding member to operative position relative to the workpiece in the work-supporting member. 110
